DESIGN FOR A DECORATIVE NAIL

Joseph Eitinger, New York, N. Y.

Application July 9, 1938, Serial No. 78,366

Term of patent 3½ years

To all whom it may concern:

Be it known that I, Joseph Eitinger, a citizen of the United States of America, residing in New York city, in the Borough of Manhattan, county and State of New York, have invented a new, original, and ornamental Design for a Decorative Nail, of which the following is a specification, reference being had to the accompanying drawing, forming part thereof, wherein,

I claim:

The ornamental design for a decorative nail, substantially as shown.

JOSEPH EITINGER.
